UNITED STATES PATENT OFFICE.

ELLSWORTH A. HAWTHORNE, OF BRIDGEPORT, CONNECTICUT.

LAMP.

1,342,215.

Specification of Letters Patent.

Patented June 1, 1920.

Application filed July 7, 1916, Serial No. 108,062. Renewed March 9, 1918. Serial No. 221,575.

To all whom it may concern:

Be it known that I, ELLSWORTH A. HAWTHORNE, a citizen of the United States, and a resident of Bridgeport, in the county 5 of Fairfield and State of Connecticut, have invented an Improvement in Lamps, of which the following description, in connection with the accompanying drawings, is a specification, like characters on the drawings representing like parts.

This invention relates to lamps, and more particularly to lamps such as are used on vehicles, and one of the purposes thereof is to provide such a lamp which can be readily brought to proper focus.

My invention will be best understood by reference to the following description, taken in connection with the accompanying drawings, wherein:

20 Figure 1 is a central vertical section through a form of lamp which will serve as an illustrative embodiment of my invention;

25 Fig. 2 is a central horizontal section through part of the lamp shown in Fig. 1;

Fig. 3 is a section on line 3—3 of Fig. 2, but on a larger scale;

30 Fig. 4 is a view similar to Fig. 3, showing the parts in a different position of adjustment;

Fig. 5 is a plan view of one of the parts arranged in a position similar to that it occupies in Figs. 3 and 4;

35 Fig. 6 is a section on line 6—6 of Fig. 1, but on a larger scale; and

Fig. 7 is a central horizontal section showing certain parts of the lamp.

The form of lamp which I have chosen, as illustrated in my invention, includes a 40 suitable casing with an interior reflecting surface, and I have here shown an exterior casing 1 and a separate reflector 3 within the same, which may be and preferably is of parabolic form. The front of this casing may be closed by a suitable bezel 5 and glazing 7, here shown as of the kind disclosed in my Patent No. 1,203,618, dated Nov. 7, 1916. I have illustrated the lamp as carrying a main light 9, disposed centrally therein, and a small pilot light 11 disposed at one side thereof. The main light 9 is mounted in a light-carrying member 13, which may be provided, as shown, with suitable bayonet slots 15 to receive 50 pins 17 carried by the light.

55 The light-carrying member 13, as shown,

extends through the reflector, which may be and preferably is provided with a ferrule or sleeve 19 to furnish an extended bearing for said member, and also through the casing to the outside thereof. Part of the casing forms a housing to receive the member 13, and in the present embodiment, a part of this housing is extended rearwardly from the main part of the casing, and may serve 60 as a handle 21 by which the lamp may be moved. The member 13 is shown as extending through a suitable aperture in the rear of the housing, and may be provided exteriorly with a switch handle or finger grip 70 23, it being understood that suitable switch means are carried by the member 13 for controlling the light or lights in the casing.

To adjust the light 9 to proper focus, the light-carrying member may be shifted in 75 its bearings in the reflector 3, and housing 21. To permit such adjustment without occasioning rotary movement of the member which would impose a strain on the connecting wires, the member 13 is locked 80 against rotation. In the present embodiment of the invention, there are two devices which tend to keep the member 13 from rotating, one of which will now be described. Preferably I provide for interlocking the member 13 with the housing 21, for example by providing the embossed rib 25 on the member which fits a recess 27 in the wall of the housing, thus forming a tongue and slot connection. Otherwise de- 90 scribed, it might be said that the housing 21 is provided with a non-circular aperture in which the light-carrying member 13 fits.

Prior to my present invention, it had been proposed to hold a similar light-carrying 95 member by forming a joint between the same and the reflector, but to do this necessitated cutting slots other than the slots 15 in the inward end of the member. Thus it was considerably weakened, and a further 100 disadvantage arose in that users would attempt to engage the lamp 9 with the guiding slots rather than with the bayonet slots similar to 15. In the present instance, the inward end of the member is slotted only to 105 receive the pins 17 on the light 9, and therefore is amply strong, and the socket provided at that end to receive the light is not likely to be distorted. Preferably, moreover, I provide the male part of the interlocking joint between the member and the 110 housing on the member, and form it by em-

bossing the rib 25. By this construction, the light-carrying member is not substantially weakened at its outer end.

The adjustment of the light-carrying member may take place from the exterior of the casing by manipulation of the projecting end of the latter. To hold the same in its adjusted position, I desirably provide means acting to jam the member in place in the housing 21. For this purpose, I may utilize one or more plates 29, each adapted to fit against the housing at one end and against the light-carrying member 13 at the other. In the present embodiment, one such plate is used. This plate is shown in plan view in Fig. 5, and by a comparison with Figs. 3 and 4, it will be seen that its length is greater than the width of the space between the member 13 and the interior surface of the housing. It will, therefore, be disposed somewhat on a diagonal as shown in Fig. 2, bracing apart the member 13 and the wall of the housing. The plate 29 is tapped at 31 to receive the screw 33 entering the housing from the exterior thereof, so that the plates 29 may be adjusted from the outside. It is apparent that, if the screw 33 is turned, the diagonal brace 29 will be tilted and act as a jaw to grip the member 13, and hold it firmly against lateral movement by exerting a wedging force between the same and the housing 21. In Fig. 3, I have shown the plate gripping part 13, and in Fig. 4 the screw has been manipulated so as to tilt the same away from part 13, and it is apparent that the latter is then released and can be easily moved backward and forward, guided by the rib 25. If desired the plates may be adjusted in such a manner as to permit voluntary adjustment of the part 13 but so that they will bear upon it in the manner of brake shoes to prevent spontaneous movement. It will be noted that the part 29 acts somewhat as does the arm of a toggle joint, and it might therefore be aptly called a toggle arm.

While the toggle arm or gripping jaw 29 is entirely inclosed within the housing 21, and is protected by the same, it is readily accessible for manipulation from the exterior of the lamp by means of the screw 33. The arrangement is such that it takes a very firm grip on the light-carrying member 13, and prevents its longitudinal movement, and it is not easily deranged on account of the vibration of the vehicle on which the lamp is carried. Furthermore, since it is tightly wedged in place, there will be no tendency for it to rattle, as is the case with threaded devices. It will be noted, furthermore, that by providing a releasable gripping member for holding the member 13 in adjusted position, adjustment may take place by a simple longitudinal sliding movement which introduces no rotative forces, and that con-

sequently no strain is imposed on the joint 25-27.

In the present embodiment of the invention, the gripping jaw 29 is shown as provided with a lug 35, adapted to coöperate with a longitudinal slot 37 on the side of the light-carrying member 13. This slot allows for the adjusting movement of the member, and at the same time, the tongue and groove joint coöperates with the tongue and groove joint 25-27 in preventing rotation of the member 13. A further advantage of this lug is that in connection with the screw 33, it provides a two-point suspension for the jaw 29, so that it is securely positioned within the housing 21, and when manipulated by means of the screw 33, will seat evenly and firmly with a strong, clamping pressure against the member 13. It will be understood, however, that, while I prefer to utilize this lug and slot construction in connection with the jaw 29, it might be omitted.

At the junction between the housing 21 and the main body of the casing 1, I preferably dispose an insulating packing 39, which may be conveniently formed of cork secured in place by a suitable adhesive, such as shellac. This packing forms a partition, which substantially isolates the space defined between the reflector 3 and the main part of the casing 1 and the space at the interior of the housing 21. As clearly seen in Fig. 1, the light-carrying member 13 extends through this packing or partition, which snugly fits the same and forms a close, frictional bearing for it in its sliding movement. If water or dirt should enter the interior of the housing 21 at the joint between the same and the light-carrying member 13 which cannot conveniently be packed in a fluid-tight manner, the packing 39 will prevent the same from entering the main space between the reflector and casing. Since the electrical connections are located in this space, they will be protected, and the reflector as well.

As clearly shown in Figs. 1 and 2, the packing 39 is formed on the side facing the reflector with a circumferential flange 41, defining a cup-shaped space 43. The purpose of this conformation of the packing or insulating partition can best be explained after the electrical connections of the lamp have been described, which I will next proceed to do, referring particularly to Fig. 1 and Fig. 7.

In the embodiment of the invention shown, the light-carrying member 13 serves as a switch socket, and the two lights 9 and 11 may be selectively controlled by the handle 21 above described. The electrical connections lead to the member 13 in the space between the outer casing 1 and interior reflector 3. I have herein shown the duplex

cable 45 entering the outer casing through an aperture, as shown, and comprising the ground cable 47, connected with the member 13 through binding screw 49, and the 5 cable 51 for the light 9 connected to the member 13 by the binding screw 53 which passes through a fiber washer 55. A large fiber washer or insulating plate 57 is carried by the member 13, and connection of 10 the cable 59 for the pilot light 11 is made through the washer 57 by means of the binding screw 61.

It will now be possible to explain the advantage of forming the packing 39 with the 15 cup-shaped portion 43. As the member 13 is moved rearwardly in adjusting the focus of the lamp 9, the small fiber washer 55 will engage with the cork packing 39. If by chance there should be any loose strands of 20 wire in the cable 51, or if the latter should become disconnected from the binding screw 13, the packing 39 will avoid a short circuit as it will prevent the cable from touching the side of the lamp body. The 25 cup-shaped depression 43 receives, as it were, the connection of the wire 51 and, extending over the same, thoroughly guards all adjacent parts of the lamp casing from such stray ends of wire as have been mentioned. 30

The large washer or plate 57 also has an insulating function. As seen from Figs. 1 and 7, it projects well forward of the points of connection of the wires, and therefore in 35 the forward movement of the member 13, it will come in contact with the reflector 3 or the sleeve 19 extending therefrom, and prevent any loose strands of wire short-circuiting on the reflector. Furthermore, quite independently of its function as an insulator 40 to prevent short-circuiting, this washer will act as a stop which, by engaging with the sleeve 19 of the reflector, will check the forward movement of the light-carrying member 13, and thus keep the same from dropping into the interior of the housing 21. In Fig. 7, the washer 57 is clearly shown in contact with the sleeve 19 of the reflector, and it is apparent that the member 13 can 45 not move any farther toward the right.

I have described in detail the embodiment of my invention here illustrated, and in so doing, have referred to the various parts by specific words. It will be understood, 55 however, that I have done this in order that the structure shown might be more readily understood and not with a defining purpose, as the various details disclosed are not of the essence.

60 What I do claim and desire to secure by Letters Patent is:

1. A lamp embodying a casing having an interior reflecting surface, a light-carrying member slidably mounted and extending 65 through said casing, and an adjustable jaw

coöperating with said casing to clamp said member against sliding movement, said jaw having a lug and slot connection with said member.

2. A lamp embodying a casing having an 70 interior reflecting surface, a housing extending rearwardly from said casing, a light-carrying member extending through said housing, and an element interposed between said member and a wall of the housing 75 and movable from the exterior of the housing to exert a wedging force tending to spread apart said light-carrying member and the housing, said element being held against rotary movement with respect both 80 to said member and said housing.

3. A lamp embodying an exterior casing and an interior reflector defining a space between them and a housing extending rearwardly from said casing, a light-carrying 85 member extending through said reflector and housing and having sliding bearing therein, means coöperating with said housing for holding said member against rotative movement, a packing member at the 90 junction of said housing and casing providing a bearing for said light-carrying member and substantially isolating the interior of said housing from the space aforesaid, and clamping means to hold said light-carrying member in selected positions of longitudinal adjustment. 95

4. A lamp embodying an exterior casing and an interior reflector defining a space between them and a housing extending rearwardly from said casing, a light-carrying member extending through said reflector and housing and having sliding bearing therein, means coöperating with said housing for holding said member against rotative movement, electric connections to said member disposed in said space, an insulating partition at the junction of said housing and casing providing a bearing for said member and substantially isolating the interior of 100 said housing from the space aforesaid, and clamping means to hold said light-carrying member in selected positions of longitudinal adjustment. 105

5. A lamp embodying an exterior casing 110 and an interior reflector defining a space between them and a housing extending rearwardly from said casing, a light-carrying member extending through said reflector and housing and having sliding bearing therein, means coöperating with said housing for holding said member against rotative movement, electric connections to said member disposed in said space, an insulating partition at the junction of said housing and casing providing a bearing for said member and substantially isolating the interior of 115 said housing from the space aforesaid, and clamping means to hold said light-carrying member in selected positions of longitudinal adjustment. 120

6. A lamp embodying an exterior casing 125 and an interior reflector defining a space

said space, and clamping means to hold said light-carrying member in selected positions of longitudinal adjustment.

6. A lamp embodying an exterior casing and an interior reflector defining an unobstructed space between them, a light-carrying member bridging said space extending through said casing and reflector and having sliding bearing therein, a tongue and groove connection between said casing and member, stop means carried by said member in said space for engagement with reflector and casing respectively to limit the longitudinal motion of said member, and clamping devices to hold said light-carrying means in selected positions of longitudinal adjustment.

7. A lamp comprising, in combination, an exterior casing and an interior reflector, a light-carrying member extending through the same and having sliding bearing therein whereby to permit adjustment of the focus of the light, a longitudinal groove in said member, a clamping device entering said groove and adapted to guide the member in its sliding movement and susceptible of screw adjustment from the exterior of the casing to brace the member from the wall thereof and hold it in selected positions of adjustment.

8. A lamp comprising, in combination, an exterior casing and an interior reflector, a light-carrying member extending through the same and having sliding bearing therein whereby to permit adjustment of the focus of the light, a longitudinal groove in said member, a clamping device having a portion entering said groove to guide the member in its sliding movement, said clamping device including a member disposed within said casing adjacent said light-carrying member and a screw entering the same and adjustable from the exterior of the casing to apply clamping pressure to said light-carrying member.

9. A lamp embodying an exterior casing and an interior reflector defining a space between them and a housing extending rearwardly from said casing forming a handle for the lamp, a light-carrying member extending through the reflector and housing and having sliding bearing therein, and a packing of yielding insulating material adjacent the junction of said housing and the main body of the casing having firm fric-

tional engagement with said member and forming a partition between the interior of said housing and said space.

10. A lamp embodying an exterior casing and an interior reflector defining a space between them and a housing extending rearwardly from said casing forming a handle for the lamp, a light-carrying member extending through the reflector and housing and having sliding bearing therein, electric connections to said member disposed in said space, and a packing of yielding insulating material adjacent the junction of said housing and the main body of the casing having firm frictional engagement with said member and forming a partition acting to prevent projection of said connections into contact with the inner wall of said housing.

11. A lamp embodying a casing and an interior reflector defining a space between them, the casing having a hollow rearward extension, a light-carrying member extending through the reflector and received in said extension and a packing member fitting the extension and having an aperture receiving said light-carrying member and providing a frictional bearing therefor.

12. A lamp embodying a casing and an interior reflector defining a space between them, a light-carrying member extending between the same, electrical conducting devices in said space connected to said member, an insulating washer carried by said member adjacent a point of connection of said conducting devices and adapted to limit movement of said member by coming in contact with adjacent parts of the lamp and thereby also preventing grounding of said conducting devices on said parts.

13. A lamp embodying a casing and an interior reflector defining a space between them, said reflector having an opening to said space, a member slidably mounted in the opening and having a socket at its end to receive an electric bulb, electrical connecting devices passing through the casing and connected to said member in said space, an insulating plate carried by said member extending forwardly of the point of connection of said devices and adapted to make contact with the reflector to limit sliding movement of the same.

In testimony whereof I have signed my name to this specification.

ELLSWORTH A. HAWTHORNE.
